UNITED STATES PATENT OFFICE.

DANIEL W. ROHRER, OF TRENTON, NEW JERSEY.

LOCK.

Application filed November 22, 1923. Serial No. 676,379.

To all whom it may concern:

Be it known that I, DANIEL W. ROHRER, a citizen of the United States, and a resident of Trenton, in the county of Mercer and State of New Jersey, have invented a new and Improved Lock, of which the following is a full, clear, and exact description.

The present invention relates to new and useful improvements in locks, and it pertains more particularly to locks of the combination type.

It is one of the primary objects of the invention to provide a new and improved mechanism whereby a lock of the sliding latch type may be used in combination with means for operating the sliding latch.

It is a further object of the invention to provide a mechanism which will operate in either direction without operating the latch.

It is a further object of the invention to provide a mechanism which will rotate in one direction without operating the latch, and, at the same time, when properly positioned with respect to the latch-operating means, will operate the latch when rotated in the opposite direction.

With the above and other objects in view, reference is had to the accompanying drawings, in which—

Figure 1 is a view in elevation showing a lock constructed in accordance with the present invention, the internal mechanism of the lock being shown in dotted lines:

Fig. 2 is a sectional view showing the mechanism of the lock;

Fig. 3 is a sectional view taken on the line 3—3 of Fig. 1;

Fig. 4 is a sectional view taken on the line 4—4 of Fig. 1;

Fig. 5 is a detail view showing the position of certain elements of the mechanism during the movement of the operating member in one direction;

Fig. 6 is a similar view showing the position of certain elements of the mechanism during movement of the operating member in the opposite direction;

Fig. 7 shows the position of certain of the elements during the operation of moving the latch;

Fig. 8 is a detail top plan view of a portion of the latch operating member.

Referring more particularly to the drawings, the reference character 10 designates a door or the like, to which the lock is adapted to be attached, and 11 designates

the lock housing, which, while it is shown in the present instance as of the "mortise" type, may be attached to one of the outer faces of the member 10.

Mounted within the housing there are two spaced guides 12, and slidably mounted between said guides 12 there is a latch member 13, the end 14 of which projects through an opening 15 in one of the walls of the housing 11. A spring 16, anchored as at 17, is adapted to normally maintain this latch member in its extended position. The latch member 13 is reciprocated between the guides 12, by an operating member 17 pivotally connected as at 18 to the housing 11, said member 17 operating in a recess 19 formed in the latch member 13. This operating member 17 is rocked about its pivotal point 18 by means of a rotating member, said rotating member 20 being carried by a shaft 21 upon which there is an operating knob or the like, 22, secured in position by means of a screw 23. The shaft 21 projects through one of the side walls of the housing 11, as more clearly shown in Fig. 4, and the operating knob 22 is attached to the outer end thereof.

Pivottally connected to one of the ends of the rotating member 20, as at 25, there is a pawl 26, and carried by one of the sides of the rotating member 20, there is a spring 27 having two fingers 28 and 29. As more clearly shown in Figs. 5 to 7, inclusive, this pawl 26 is notched out on its end, as at 30, and said notched out portion is adapted when the rotating member 20 is properly positioned to engage the edge of the operating member 17, in which position it is clearly shown in Figs. 2 and 7, the spring 27 finger 29 serving to maintain the pawl in engagement with the operating member.

With the parts in the position shown in Fig. 2, if the rotating member 20 is moved to the right, the pawl 26 will rock the operating member 17 about its pivotal point 18 and move the latch to the dotted-line position shown and permit of releasing of the lock. If, however, the rotating member 20 is moved to the left or in an anti-clockwise direction, the pawl will be disengaged from the operating member 17. If this member 20 is rotated a complete revolution, the pawl 26 will wipe over the operating member 17, as is shown in Fig. 6. If with the parts in the position shown in Fig. 2, the operating member 20 is moved to the left in

an anti-clockwise direction only far enough that the pawl slips off the operating member 17 and is then turned to the right, the pawl 26 will wipe by the operating member 17, as shown in Fig. 5. By this construction it is apparent that the only time at which the pawl is capable of operation of the operating member 17, is when the notched part 30 of the pawl is in engagement 10 with the edge of the operating member 17, and this position of the parts is determined by a predetermined position of the operating knob 22, it being understood that said knob carries a plurality of calibrations in 15 order that the position of its pawl may be determined at all times by one authorized to use the lock.

What is claimed is:

1. In a lock of the type set forth, a housing, a latch member slidably mounted therein, an operating member pivotally mounted in the housing and serving to reciprocate said latch member, rotary means for rocking the operating member to operate the latch member, and a pivotal pawl carried by the rotary member and adapted to engage the operating member and rock the same about its pivotal point.
2. In a lock of the type set forth, a housing, a latch member slidably mounted therein, an operating member pivotally mounted in the housing and serving to reciprocate

said latch member, rotary means for engagement with the operating member to rock the same about its pivotal point and operate 35 the latch member, and a pivoted pawl carried by said rotary means and adapted for engagement with the operating member to reciprocate the latch member.

3. In a lock of the type set forth, a housing, a latch member slidably mounted therein, an operating member pivotally mounted in the housing and serving to reciprocate said latch member, rotary means for engagement with the operating member to 40 rock the same about its pivotal point and operate the latch member, and a pivoted pawl carried by said rotary means and adapted for engagement with the operating member to reciprocate the latch member, 45 said pivoted pawl having a notched-out portion adapted to receive one of the edges of said operating member.

4. In a lock, a latch member, an operating member pivotally connected to the lock 50 and to said latch member, rotary means for operating said operating member, means for rotating said rotary means, and a pivoted spring-actuated pawl carried by said 55 rotary means and adapted for engagement with the operating member to move the same about its pivotal point to reciprocate the latch member.

DANIEL W. ROHRER.
